CLAIM

The ornamental design for an adhesive dispensing nozzle, as shown and described.

DESCRIPTION

FIG. 1 is a front view of the adhesive dispensing nozzle; FIG. 2 is a right side view of the adhesive dispensing nozzle shown in FIG. 1;

FIG. 3 is a left side view of the adhesive dispensing nozzle shown in FIG. 1;

FIG. 4 is a top view of the adhesive dispensing nozzle shown in FIG. 1;

FIG. 5 is a bottom view of the adhesive dispensing nozzle shown in FIG. 1;

FIG. 6 is a rear perspective view of the adhesive dispensing nozzle shown in FIG. 1; and,

FIG. 7 is another rear view of the adhesive dispensing nozzle shown in FIG. 1.

The broken lines show represent portions of an adhesive dispensing nozzle and form no part of the claimed design.
